MATERNITY SLIP

Burnis Devin, Oakland, Calif., assignor to Kalin Corporation, San Francisco, Calif., a corporation of California

Application June 17, 1947, Serial No. 755,118

2 Claims. (Cl. 2—73)

1

The invention, in general, relates to ladies' undergarments and more particularly relates to an improved slip especially useful in maternity cases to meet increasing sizes of an individual during the period of maternity.

It is perhaps well known that various types of maternity slips have been introduced to the market in recent years for enhancing the comfort of the wearer under conditions of maternity, and that many of such types of slips are featured by the inclusion of means to prevent strain on the abdomen. However, the majority of the slips heretofore marketed to fill this need are of somewhat complex make requiring undue labor for producing or manufacturing the same, and are relatively expensive for the limited use to which they are put. Often, it has become necessary for the individual in maternity cases to purchase two or more slips to meet the variation in size during such maternity period. The present invention is directed to obviating inherent disadvantages relating to manufacturing costs and processes and to provide an all purpose slip eminently suitable for wear during the entire period of maternity.

A primary object of the present invention is to provide an improved maternity slip which can be worn during the entire period of maternity with but slight periodic adjustments to meet the increasing size of the individual.

Another important object of the invention is to provide an improved maternity slip of the indicated nature which is additionally characterized by the provision therein of but a minimum of elements which afford adjustability of size but which do not deleteriously affect the appearance of the slip on the individual nor present undue bulkiness.

A still further object of my invention is to provide an improved maternity slip of the aforementioned character embodying novel adjustability features which can be inserted into the garment during manufacture at a minimum of additional expense and with a minimum of labor.

The foregoing and other objects of the invention, together with some of the advantageous features thereof will appear from the following description of a preferred embodiment of the invention which is illustrated in the accompanying drawings. It is to be understood that I am not to be limited to the precise embodiment shown, nor to the precise arrangement of the various parts thereof, as my invention, as defined in the appended claims, can be embodied in a variety and plurality of forms.

2

Referring to the drawings:

Figure 1 is a front elevational fragmentary view of a preferred embodiment of the invention.

Figure 2 is a rear elevational fragmentary view of the preferred embodiment of the invention, parts being cut away to illustrate the construction.

Figure 3 is a sectional view of the preferred embodiment of the invention, this view being taken on the line 3—3 of Figure 1.

Figure 4 is a sectional view similar to Figure 3 but illustrative of the tucking or folding of the garment as carried on the body of the individual at early periods of maternity.

In its preferred form, the improved maternity slip of my invention preferably comprises a front portion having a pair of slits therein adjacent to the sides thereof, a length of tape fastened to the inner side of said front portion, a pair of relatively long straps; one of said pair of straps being fastened to said tape on the inside of said front portion and extending through one of said slits at the opposite side of said front portion, and the other of said long straps being fastened to said tape and extending through said other slit, and means including a buckle and short straps for adjusting the size of the slip by pulling said straps attached to said tape through said buckle.

As illustrated in the annexed drawings, my improved maternity slip includes a front portion

30 12 integral with or sewn to a back portion 13, the slip as an entirety being designated by the reference numeral 11 and being manufactured from any desired material such as silk, rayon, cotton or other light-weight material. A pair of 35 shoulder straps 14 and 16 are sewn to the front and back, as indicated, and these straps are provided with conventional clips and links 17 and 18, respectively, for ready adjustment to length all in the conventional manner. A row of stitching paralleling the top of the slip affords a convenient reinforcing hem 19 at the top of the garment.

In accordance with my invention, means are inserted in my improved maternity slip during 45 the manufacture thereof for affording ready and convenient adjustment of the size thereof to meet varying increased sizes of the individual wearer during the period of maternity. These means preferably comprise the provision of two slits 21 in the front 12 of the garment which are spaced widely apart, as shown, and lie closely adjacent to the sides thereof. These adjustment means also include a pair of relatively long straps 23 and 24, together with two shorter straps 25 of 55 fixed length, the latter being fastened at their

one ends by means of stitching 26 at two spaced points on the outer side of the front 12 of the slip. The relatively long straps 23 and 24 extend through the slits 21 at the sides of the garment and are anchored, by means of stitching 27 at two spaced points on the inner side of the front portion 12 of the slip; it being understood that these long straps 23 and 24 cross one another and are passed through a loop or tunnel 28 on the inside of the front 12.

To avoid likelihood of tearing the material when the long straps 23 and 24 are pulled upon in adjusting the slip for size, I preferably stitch a length of tape 30 to the inner side of the front 12 to afford reinforcement, and sew the straps 23 and 24 directly to the tape 30 at the stitched points 27. With particular reference to Figure 2 of the drawings, it will be noted by virtue of the cut away portion of this view illustrating the inside of the front portion 12, that the strap 23 extends from stitched point 27 at the left through tunnel 28 and thence through the slit 21 at the right of the view to be brought into accessibility at the left front of the garment, as viewed in Figure 1. Similarly, the long strap 24 extends from the stitched point 27, indicated at the right of Figure 2, towards the left through tunnel 28 and the slit 21 at the left of Figure 2 to be brought to accessibility at the right front of the garment as viewed in Figure 1. The front accessible portions of the long straps 23 and 24 are passed through suitable, conventional buckles 35 and 36 to which the short straps 25 are attached, whereby the width or the size of the slip can be varied by manipulation of the four straps 23, 24 and 25 through the two buckles 35 and 36.

In Figure 4 of the annexed drawings, I have indicated the improved maternity slip of my invention at approximately its smallest size wherein the straps 23 and 24 have been pulled through the buckles 35 and 36 to pinch in the front 12 of the garment, as indicated by the overlapping folds 37 formed by reducing the garment size. Whenever it is desired to widen or increase the size of the slip, it is only necessary to manipulate the long and short straps 23, 24 and 25 to the desired extent. It is to be understood that the improved maternity slip of my present invention can be manufactured in a range of different sizes to meet the varying sizes of women; and that one given size for each size or range will suffice for an individual of that given normal size, during the entire period of maternity. In Figure 3, there is depicted the same slip as shown in Figure 4 after the various straps 23, 24 and 25 have been manipulated through the buckles 35 and 36 to increase the size to its fullest extent.

It is to be understood that the appended claims are to be accorded a range of equivalents commensurate in scope with the advance made over the prior art.

I claim:

1. An adjustable maternity slip comprising a front portion having a pair of spaced slits therethrough adjacent to the sides thereof at the waist line, a pair of relatively long straps each having one end thereof secured to the inside of said front portion adjacent said slits; each of said straps extending through one of said slits on the side of said front portion opposite to the side to which it is attached to the inside of said front portion; a pair of relatively short straps of fixed length each secured at their one end to the outside of said front portion adjacent the center thereof, and a pair of buckles secured to the other ends of said short straps; said buckles being adapted adjustably to receive the extended ends of said long straps at the front of the slip whereby the slip may be adjusted as to size.

2. An adjustable maternity slip consisting of a back portion, a front portion secured to said back portion, said front portion having a pair of spaced slits therethrough adjacent to the sides thereof at the waist line, a pair of relatively long straps each having one end thereof secured to the inside of said front portion adjacent to said slits; each of said straps extending through one of said slits on the side of said front portion opposite to the side to which it is attached to the inside of said front portion; a pair of relatively short straps of fixed length each secured at their one end to the outside of said front portion adjacent to the center of said front portion and means secured to the other end of said short straps for adjustably receiving the extended ends of said long straps at the front of the slip.

BURNIS DEVIN.
